PIT TYPE FURNACE

James M. Guthrie, Crafton, Pa., assignor to Lof-tus Engineering Corporation, Inc., Pittsburgh, Pa., a corporation of Maryland

Application March 8, 1945, Serial No. 581,626

5 Claims. (Cl. 263—43)

1

My invention relates to pit-type furnaces, particularly pit-type furnaces for heating or soaking ingots of steel or other metal, preparatory to forging, rolling or other treatment, and the invention consists in certain new and useful improvements in the structure of such furnaces, whereby more efficient and more uniform heating of ingots or other articles may be obtained.

The art is familiar with a furnace known as the center-fired pit. As its name suggests, the pit is fired centrally, through its bottom or hearth, and the burning column of fuel streams vertically upward between the charge of ingots supported on the pit bottom around the burner opening. The stream of flames impinges against the cover of the pit and spreads, umbrella like, over the charge, and then the flames and hot products of combustion descend from the "umbrella" in streams spaced radially outward from the burning column sustained by the central burner. Upon approaching the bottom of the pit the streams of hot waste gases find egress through outgo ports, which open through the pit side walls and communicate with heat-exchange means that are effective to salvage large quantities of residual heat from the gases and to transfer the heat to the combustion air which is fed to the burner. While many advantages have been recognized in the use of the center-fired pit, several disadvantages are to be noted: For example, the arrangement of the burner in the center of the pit floor results in a reduction in the ingot capacity of a pit of given size, the capacity of a pit being in general proportional to the area of the pit bottom which is available to receive ingots. Consequently, in order to obtain a specified pit capacity, it has been necessary to build a larger and more costly pit than would be the case if the entire bottom of the pit were available for the support of ingots. Additionally, it may be noted that the impingement of a stream of burning fuel against the pit cover is deleterious to the cover structure. Furthermore, when the burner in service fails to function properly, the entire pit must be shut down, it being understood that it is not uncommon for burners to require attention over prolonged periods of service.

In accordance with my present invention, I aim to eliminate the objections of the center-fired pit, while obtaining its more important advantages, as well as obtaining better distribution of the flow of the flames and hot gases between and over the surfaces of all of the ingots charged and supported upon the hearth of the pit.

The invention will be understood upon the ref-

2

erence to the accompanying drawings, in which:

Figure 1 is a fragmentary view in plan of a battery of pits, affording an exemplary embodiment of the invention;

5 Figure 2 is a view to larger scale and in vertical section of one of the pits, the plane of section being indicated at II—II in Figure 1;

Figure 3 is a view in cross section through the pit, as seen on the plane III—III of Figure 2; and

Figure 4 is a view on the plane IV—IV of Figure 2, showing the pit in side elevation, and illustrating a set of heat-exchange units in vertical section.

15 The pit furnace of the invention may be constructed as a unit having a single pit, or it may have a battery of pits, as indicated by the reference numeral 2 in Figure 1. The pits are advantageously formed square or rectangular as viewed 20 in plan, with their peripheral walls 3, 3 and 4, 4 internally curved outwardly to increase the durability and sturdiness of construction. The furnace structure is built of refractory brickwork borne on suitable concrete foundations 5; the pit 25 proper is supported upon a platform of steel channels 6, laid "toes down" on beams 7 that rest upon the foundation; and the structure is encased with steel plate, laterally reinforced and tied by means of conventional steel buckstays 30 and braces, the latter members being omitted from the drawings for the sake of clarity of illustration.

35 The hearth or bottom 8 of the pit includes one or more cleanout openings 9, which are normally filled with the coke breeze 10, or other suitable material which provides the floor upon which the ingots 11 stand, as shown in Figure 2. The pit is provided with a cover 12 that is temporarily removable to permit the ingots to be 40 charged into the pit and removed. It will be observed that the entire area of the bottom of the pit is available for the support of ingots, with the ingots arranged and spaced properly in accordance with ingot size and shape.

45 My present invention relates particularly to the organization of a plurality of burners for firing each pit, together with an effective arrangement of waste gas ports for removing the hot waste gases or products of combustion from the pit, all to the end that a more effective distribution of heating effect may be established and maintained throughout all portions of the pit chamber, not only when the pit is fired at a maximum heating capacity but also when the

burners are turned down for soaking or "holding" the charge of ingots.

In its general aspects the invention constitutes certain new and useful improvements in the pit furnace disclosed in United States Letters Patent No. 2,085,811, granted July 6, 1937, to Fred H. Loftus. In the structure of this patent two burners are provided in one side or end wall of the pit and below such burners outgo ports open through the same wall into two regenerators. Both burners are adapted to be fired continuously while the regenerators are alternately operated, after the manner that the regenerators of an open hearth furnace are operated, to furnish preheated combustion air to the burners.

In improvement of such arrangement, I provide a burner 13 for each corner of the pit, and it is of the essence of the invention that the burners comprise long-flame luminous burners—burners which project long columns or jets of luminous flame transversely of the upper portion of the pit chamber and preferably above the tops of the ingots therein. It will be perceived that two of the four burners 13 are arranged in each of the opposite walls 3, 3 of the pit, with the burners in each wall spaced apart a relatively great distance peripherally of the pit. It is important to note that the burners in the opposite walls are so complementarily inset or spaced from the adjacent pit corners that the streams of flame (note arrows A, Figure 1) projected by the burners in one wall are interdigitated with respect to the streams of flame directed across the pit by the burners in the opposite wall. One burner in one of the walls 3 projects its flame between and in substantial parallelism with the flames projected by both of the burners in the opposite wall. This arrangement of long-luminous-flame burners contributes to the obtainment of a more perfect distribution of firing and heating effect throughout the pit, not only when the burners are firing at maximum capacity, but also when they are firing at reduced capacity, as is the case when the steel approaches and reaches the desired ultimate temperature. Thus, optimum heating is realized, and localized "cool" spots in the pit and in portions of the ingot charge are avoided when burner turn-down is made. An additional advantage is to be noted:

When opening a pit in accordance with usual practice, the firing rate of the burner or burners is reduced, and the cover is moved to one side or the other, depending upon which side of the center line of the pit it is desired to remove or to charge ingots. The cover is not removed entirely from the mouth of the pit, but is moved only to the extent necessary to give the required access, since it is desirable to minimize the loss of heat always encountered when a pit is opened. By virtue of the burner arrangement herein disclosed, when the pit is opened the flames of the burners provide a screening effect across the area of the opening and thereby serve to minimize the loss of heat from the pit. This effect is obtained regardless of which side of the pit is opened.

Advantageously, all of the burners (two burners in this case) in each wall 3 are mounted in angular position relatively to the walls 3. One of the burners in each wall 3 directs flame tangentially, or approximately so, with respect to the adjacent wall 4; that is, the burners which in the herein illustrated structure appear at the lower right-hand corners of the pits 2 (Figure 1), and the burners which appear at the upper left-hand corners, are arranged to direct their flames

with tangential effect relatively to the adjacent walls 4. This arrangement, coupled with the effect of the angularity upon the interdigitated flames themselves, operates to maintain a beneficial swirl of luminous flames at or above the tops of the ingots.

Below the burners, outgo ports 14 open through the walls 3, 3 and lead into heat-exchange units 15 for preheating the combustion air that is fed through a duct system 16 to the burners. The arrangement of the outgo ports is such that the drafting of waste gases from the bottom of the pit is substantially symmetrical with respect to the firing effect of the burners above the ports. While a single outgo port, or row of three or more ports, may be arranged in each wall 3 to give this desired effect, I advantageously provide one outgo port for each burner, with each port arranged substantially directly below the associate burner.

The effect of the described burner and outgo port organization is to insure at all rates of firing a uniform distribution of heat throughout the pit chamber and its charge. As the art well knows, a luminous flame burner is one whose flame contains unburned particles or molecules of fuel. In the travel of the jetted fuel from the burner these particles are progressively heated to incandescence and burned, so that the heat release of the flame is distributed over a long path of flame travel, rather than being concentrated at a point located a relatively short interval from the burner. Accordingly, my provision of interdigitated streams of long luminous flames at the tops of the ingots does not mean that combustion is completed above the tops of the ingots. On the contrary, burning tongues of flame are drawn downward between the ingots as well as between the ingots and the pit walls, such movement of the flames being promoted by the pressure created by the injected burning fuel and air at the top of the pit, plus the suction of the draft acting through the outgo ports. A beneficial prolongation and distribution of combustion, and a thoroughly disseminated movement of the hot waste gases, are provided in the pit at all firing rates.

The heat-exchange means 15 comprise recuperators, and I provide a set of two recuperator chambers 17 on each side of each pit, one recuperator chamber for each outgo port 14. Each recuperator chamber includes a bank of heat-exchange tubes 18 extending between, and opening at their opposite ends through, walls 19 and 20. The waste gases streaming from each outgo port enters the top of its associate recuperator chamber, and flows downwardly between and over the surfaces of the tubes 18 into a flue 31 leading to a suitable stack, or exhaust fan, which is not shown but will be understood to be of conventional construction. In this case it will be seen that the two recuperator chambers on each side of the pit discharge into a common flue 31, and it will be also understood that the usual stack or flue dampers or valves will be provided in the flues 31 leading from the two sides of the pit to provide, in conjunction with conventional furnace controls, proper pressures within the pit.

Between the two recuperator chambers 17 on each side of the pit, an air chamber is provided, and this air chamber is divided by a horizontal partition 30 into upper and lower compartments 21 and 22. Air for combustion is introduced by a cold air inlet pipe 23 into the lower air compartment 22, whence it flows laterally in divided stream through the tubes 18 in the lower half

of the bank of tubes in each set of chambers 17. The air, emerging from these lower tubes into header chests 24, rises and then flows inwardly through the tubes in the upper half of the bank of tubes in each chamber 17. The air emerges into the upper air compartment 21, and in the course of its flow through the recuperator structure the air takes up large quantities of heat yielded by the waste gases delivered through ports 14. The highly heated air is delivered from compartment 21 to the duct system that supplies the combustion air to the burners 13 on the corresponding side or end of the pit. More particularly, the heated air flows from compartment 21 to a duct 25 that delivers into a manifold 26, and manifold 26 opens at its opposite ends into the air inlets 27 of each burner. A valve or damper 28 is provided in the manifold between the inlet duct 25 and each burner, whereby the combustion air to each burner may be properly proportioned to the rate of fuel delivered by the fuel nozzle 29. Conventional proportioning mechanism for air-fuel ratio control and temperature control may be incorporated in the furnace structure.

Within the terms of the appended claims certain variations and modifications of the structure described may be provided or practiced without departing from the spirit of the invention.

I claim as my invention:

1. In a pit-type ingot furnace of general rectangular form in plan having refractory walls, a hearth for supporting ingots on end, a movable cover, burner means for delivering burning columns of fuel and air into the furnace, piping for delivering fuel and combustion air to said burner means, a flue system for leading the hot products of combustion from the furnace, and heat-exchange means arranged with said flue system for preheating said combustion air; the improvements herein described wherein said furnace includes a combustion space between the tops of said ingots and said cover and said burner means comprise two burners opening into said combustion space through each of two opposite walls (termed burner walls) of said furnace, the burners opening through one burner wall being offset with respect to the burners opening through the opposite burner wall, whereby the burning columns delivered by said burners are interdigitated as viewed in plan, providing over the horizontal expanse of said combustion space above the ingots a turbulent body of flames and hot gases, and outlet ports opening into said flue system through the furnace walls below said burners, whereby a distributed flow of flames and hot gases is drawn downwardly from said body and caused to stream over and around the bodies of the ingots in said furnace.

2. In a pit-type ingot furnace of general rectangular form in plan having refractory walls, a hearth for supporting ingots on end, a movable cover, burner means for delivering burning columns of fuel and air into the furnace, piping for delivering fuel and combustion air to said burner means, a flue system for leading the hot products of combustion from the furnace, and heat-exchange means arranged with said flue system for preheating said combustion air; the improvements herein described wherein said furnace includes a combustion space between the tops of said ingots and said cover and said burner means comprise two burners opening into said combustion space through each of two opposite walls (termed burner walls) of said furnace, the

burners opening through one of said burner walls being angled toward one of the side walls interconnecting said burner walls and the burners opening through the other of said burner walls being angled toward the other side wall interconnecting said burner walls, said angled burners being offset, whereby the angled columns of burning fuel delivered by said burners are interdigitated as viewed in plan, providing over the horizontal expanse of said combustion space above the ingots a turbulent body of flames and hot gases, and outlet ports opening into said flue system through the furnace walls below said burners, whereby a distributed flow of flames and hot gases is drawn downwardly from said body and caused to stream over and around the bodies of the ingots in said furnace.

3. In a pit-type ingot furnace of general rectangular form in plan having refractory walls, a hearth for supporting ingots on end, a movable cover, burner means for delivering burning columns of fuel and air into the furnace, piping for delivering fuel and combustion air to said burner means, a flue system for leading the hot products of combustion from the furnace, and heat-exchange means arranged with said flue system for preheating said combustion air; the improvements herein described wherein said furnace includes a combustion space between the tops of said ingots and said cover and said burner means comprise two burners opening into said combustion space through each of two opposite walls (termed burner walls) of said furnace, the burners opening through one burner wall being offset with respect to the burners opening through the opposite burner wall, whereby the burning columns delivered by said burners are interdigitated as viewed in plan, providing over the horizontal expanse of said combustion space above the ingots a turbulent body of flames and hot gases, and outlet ports opening into said flue system through said burner walls, said outlet ports being located below said burners and being arranged substantially symmetrical with respect to the burners as viewed in plan, whereby a distributed flow of flames and hot gases is drawn downwardly from said body and caused to stream over and around the bodies of the ingots in said furnace.

4. In a pit-type ingot furnace of general rectangular form in plan having refractory walls, a hearth for supporting ingots on end, a movable cover, burner means for delivering burning columns of fuel and air into the furnace, piping for delivering fuel and combustion air to said burner means, a flue system for leading the hot products of combustion from the furnace, and heat-exchange means arranged with said flue system for preheating said combustion air; the improvements herein described wherein said furnace includes a combustion space between the tops of said ingots and said cover and said burner means comprise two burners opening into said combustion space through each of two opposite walls (termed burner walls) of said furnace, the two other opposite walls (termed side walls) of said furnace being outwardly bowed as viewed in plan, the burners in said burner walls being angled relatively to said side walls, whereby the burning columns delivered by the burners in one of said burner walls are angled toward one of said outwardly bowed side walls and the columns delivered by the burners in the other of said burner walls are angled toward the other of said outwardly bowed side walls, said burning columns expanding laterally to provide a turbulent

body of flames and hot gases distributed over the horizontal expanse of said combustion space above the ingots in the furnace, and outlet ports opening through the furnace walls into said flue system at points located near said hearth for effecting a distributed flow of the flames of hot gases downwardly from said combustion space and over and around the bodies of the ingots in said furnace.

5. In a pit-type ingot furnace of general rectangular form in plan having refractory walls, a hearth for supporting ingots on end, a movable cover, burner means for delivering burning columns of fuel and air into the furnace, piping for delivering fuel and combustion air to said burner means, a flue system for leading the hot products of combustion from the furnace, and heat-exchange means arranged with said flue system for preheating said combustion air; the improvements herein described wherein said furnace includes a combustion space between the tops of said ingots and said cover and said burner means comprise two burners opening into said combustion space through each of two opposite walls (termed burner walls) of said furnace, the two other opposite walls (termed side walls) of said furnace being outwardly bowed as viewed in plan, the burners in said burner walls being angled relatively to said side walls, whereby the burning columns delivered by the burners in one of said burner walls are angled toward one of said out-

wardly bowed side walls and the columns delivered by the burners in the other of said burner walls are angled toward the other of said outwardly bowed side walls, said burning columns expanding laterally to provide a turbulent body of flames and hot gases distributed over the horizontal expanse of said combustion space above the ingots in the furnace, and outlet ports opening into said flue system through said burner walls at points located beneath said burners and substantially symmetrical with respect to said burners as viewed in plan, whereby a distributed flow of flames and hot gases is drawn downwardly from said body and caused to stream over and around the bodies of the ingots in said furnace.
